CLAIM

The ornamental design of a chandelier, substantially as shown and described.

DESCRIPTION

FIG. 1 is a perspective view of a chandelier embodying the design of the present invention.

FIG. 2 is a front side elevational view of the chandelier illustrated in FIG. 1.

FIG. 3 is a rear elevational view of the chandelier illustrated in FIG. 1.

FIG. 4 is a left side elevational view of the chandelier illustrated in FIG. 1.

FIG. 5 is a right side elevational view of the chandelier illustrated in FIG. 1.

FIG. 6 is a top view of the chandelier illustrated in FIG. 1; and,

FIG. 7 is a bottom view of the chandelier illustrated in FIG. 1. The portions shown in broken lines do not form part of the claimed design.
